UNITED STATES PATENT OFFICE

FRANCES M. DE LEON, OF NEW YORK, N. Y.

UNIT TWIN BED

Application filed December 1, 1928. Serial No. 323,153.

The invention relates to improvements in beds and has particular reference to means disposed in the structure of the standard double bed for rendering such structure a unit twin-bed.

An object of the invention resides in the providing of a standard double bed structure of either the metal frame type or the wood frame casement type carrying the box-spring transverse supporting slats, with a centrally disposed supporting member composed of two angle iron supporting bars, engaging in the first instance the frame ends of the metal bed, and in the second instance each of the lateral or transverse slats, said bars being attached together by means of plates to form a unit supporting structure, and of disposing upon each section a box-spring and mattress, to produce substantially two separate but yet attached twin beds.

Another object of the invention lies in the producing of a twin bed structure out of the ordinary type of standard double bed, wherein, by the utility of distinct box springs and mattresses for each section of the bed two persons may use the bed, yet utilizing less space than the double beds, have a result of a separate or independent bed for each person so using it, and yet when made up in disuse provide in appearance a unit structure of the standard double bed type.

Another object of the structure anticipates a serviceable hospital bed since by disposing in the usual type of bed the invention involved herein, it will provide a bed structure whereon a patient may be quickly and readily moved from one section to the other thereof, eliminating entirely any possible or certainly an excessive amount of disturbing such patient. Again the invention may be employed in a manner wherein the supporting stringer bars may be disposed upon any type of bed, either of an article of new manufacture, or upon the standard type of bed of the general class of standard article of manufacture.

In the following I describe the essential embodiment of the invention the features thereof being more clearly defined herein-after in the claims.

In the drawings Fig. 1 is a top plan view of the standard metal bed, showing the disposition thereon of the supporting stringer bars, for rendering such double bed a unit twin bed structure; Fig. 2 is a transverse sectional view of unit twin-bed structure, assembled from the standard double bed type, and showing the disposition thereon of the individual box springs and separate mattresses therefor; Fig. 3 is a perspective view of the double stringer supporting bars or angle iron supports; Fig. 4 is a cross sectional view of a bed of any type made into a hospital bed employing the invention as disclosed herein; Fig. 5 is an enlarged detail view of the bed when converted into a unit twin-bed, showing how the same may be made up to provide in appearance the usual form of standard double bed; and Fig. 6 is a detail cross sectional view of the unit bed converter sustaining bars illustrating the manner in which said bars are fastened together to provide the unit stringer member.

Similar numerals of reference indicate similar parts throughout the several views.

In the drawings 1 designates the standard type of double bed frame of the metal form having a head piece 2, a foot piece 3, side supporting members 4 and end supports 5. The wooden casement type of bed comprises the same head piece 2, foot piece 3 and side members 6, and one or more transverse supporting slats 7 for supporting the box spring of a bed structure.

To render a standard type of bed of any form a unit twin-bed, central supporting angle iron bars 8 and 9 attached together in spaced apart relation by means of plates 10 are disposed at their ends 11 upon either the supports 5 or slats 7, and individual box springs 12 are disposed upon one bar 4 and the duplex stringer bar 8—9, and independent mattresses 13 are mounted upon the supporting structure of a unit twin-bed.

Said supporting stringer bars 8 and 9 may have formed therein near opposite ends apertures 14 arranged to engage pins 15 on the bed frame, thus preventing lateral displacement; and in order to render said structure standard equipment for any type of bed, said

bars 8 and 9 may have formed therein cut-outs 16 adapted to receive the slats 7 of the wooden frame type of bed. By disposing said cut-outs 16 in such centralized supporting media a universal type of quick-change device is provided to effect the required result of immediately changing an ordinary type of double bed into a bed composed of two or twin-beds of separate utility, yet constituting a single structure.

In Fig. 5 of the drawings the bed structure shows a unit twin-bed assemblage made up as the ordinary double bed form each section thereof being provided with separate coverlets, and the latter in turn being covered by a single spread.

In Fig. 4 of the drawings the invention is applied to a hospital type of bed and shows the ease with which a patient reclining thereon may be shifted from one part to the other, and the mattress and supporting springs and frames changed without the noticeable discomfort to one reclining thereon.

The invention may be varied in many ways without departing from the scope of the invention.

By making the bed converter sustaining member of two separated angle-irons, as shown in Figure 3, a rigid, light and economical stringer is provided, the vertical portions of which hold the box springs 12 apart and the horizontal portions of which support said springs at one side. Moreover, a space is provided between the vertical portions of the duplex stringer into which the edges of the bed clothing, covering the independent mattresses, may drop, avoiding bulk of material along the center of the bed. Such space is shown in all the figures of the drawings.

What I claim and desire to secure by Letters Patent of the United States, is:—

1. A bed converter comprising a duplex stringer formed of two angle-irons L-shaped in cross-section and arranged in spaced apart relation with their vertical walls adjacent and parallel, their horizontal walls directed away from each other, and their channeled sides presented upwardly providing two parallel receptacles for the adjacent side bars of single mattresses, and means for connecting said angle-irons and for holding them in the relation stated.

2. A structure such as defined in claim 1, wherein the oppositely extending portions of the angle-irons are provided with cut-outs for the reception of bed slats.

3. In combination with a bedstead having end supporting members, a bed converter such as defined in claim 1, adapted to rest upon said members, and means for holding said converter from lateral displacement on said members.

4. In combination with a bedstead and a converter such as defined in claim 1, two box springs supported, respectively, upon the side

bars of the bedstead and upon the laterally extending members of the converter, whereby the box springs are permanently held in spaced apart relation providing a narrow space between them for the edges of the bed clothes.

5. In combination with a double bed having side and end supports, a duplex converter adapted to rest on said end supports and parallel with the sides of the bedstead, independent box springs mounted on said side supports and converter, the latter having means for holding the box springs permanently apart to provide a space between them, and separable interacting means between the converter and end supports of the bed for preventing lateral displacement of said converter, substantially as described.

In testimony whereof, FRANCES M. DE LEON has signed her name to this specification this 30th day of October, 1928.

FRANCES M. DE LEON.
